A. PFLANTZER

GARMENT SUPPORTER

Filed March 19, 1924

INVENTOR

Alanson Pflanzer
BY
John D. Morgan,
ATTORNEY

UNITED STATES PATENT OFFICE.

ABRAHAM PFLANTZER, OF NEW YORK, N. Y.

GARMENT SUPPORTER.

Application filed March 19, 1924. Serial No. 700,220.

My invention relates to garment holders for general use. It relates more particularly to such a garment holder in which a fabric will be firmly and positively held. It further relates to such a garment holder in which the finest fabric will not be injured by its constant use.

I have shown my garment holder as clamping and holding the top of a stocking and, in another form, as a sleeve holder, but of course it is to be understood that these are merely illustrative, for if the device is made of the proper size it can be used to support any suitable article as, for example, supporting the ends of trousers from a pole in a closet.

My invention further relates to certain articles of manufacture, combinations, and details of construction to be more fully hereinafter described and pointed out in the claims.

In the accompanying drawings the same reference numerals refer to similar parts in the several figures.

Fig. 1 is a vertical section through my preferred form showing the clamping jaws closed and in their operative position;

Fig. 2 is a side elevation showing the clamping jaws open and ready to clamp the end of a stocking, or other suitable fabric;

Fig. 3 is a top plan view;

Fig. 4 is a horizontal section on the line 4—4 of Fig. 2;

Fig. 5 is a plan view of the blank from which my garment holder is preferably stamped;

Fig. 6 is a detail vertical section on the line 6—6 of Fig. 1;

Fig. 7 is a plan view of a duplex garment holder formed by two of my separate garment holders;

Fig. 8 is another modification, similar to Fig. 7, except that the two garment holders are riveted together instead of being connected by a spring.

My garment holder is preferably formed by stamping it from sheet metal, making a blank 1 shown in Fig. 5. The end 2 of the blank is preferably provided with ears 3, 3. The other end 4 of the blank is provided with two slots 5 and 6, forming between them an integral tongue 7. This end 4 of the blank is also preferably struck up to form a transverse groove 8, shown in dotted lines in Fig. 5, but more clearly in Fig. 1. In bending the blank, it is first bent along

the dotted line 9 and then on the dotted line 10, so as to bring the end 4 over the end 2, the portion of the blank lying between the dotted lines 9 and 10, forming the base member 11 to which any suitable supporting means such as a strap 12 may be secured, the other part of the strap being secured to a woman's corset, or any other suitable support.

To permit the fabric 13, as for example a silk stocking, to be clamped without injury, I face the end 2, which is the fixed jaw of the garment holder, with some yielding material, such as rubber 14, though felt or any other suitable material may be used. This facing 14 is secured on the fixed jaw 2 by bending over the ears 3, 3, as shown in Figs. 1 and 4.

To cooperate with the fixed jaw 2, I employ a movable jaw 15 preferably formed out of another stamping and provided with similar ears 16, 16, which are bent over to hold the yielding facing 17 of rubber, felt or other material. This movable jaw is connected in any suitable manner to the tongue 7, preferably by means of a rivet 18, so that the movable jaw 15 moves with, and is supported by, the spring tongue 7, as shown in Fig. 1. On the end 19 of the spring tongue 7 I mount a bar or lug 20. Connected with the end of the spring tongue is a button 21 having a shank 22, which moves in the slot 23 formed in the end 24 of the member 4, see Fig. 6.

When the stocking 13, or other fabric, is drawn up into my garment holder, the parts are in the position shown in Fig. 2. By then pressing down upon the spring tongue 7, the movable jaw 15, with its rubber or other facing 17, is caused to grip the stocking 13 firmly against the rubber or other facing on the fixed jaw 2, and is held in that position as soon as the bar or lug 20 snaps into the locking groove 8. It is impossible for the stocking, or other fabric 13, to be accidentally withdrawn from my garment holder for it is held both by spring pressure and the lock, which prevents the spring means yielding, until such time as the wearer desires to release the stocking or other fabric 13. This can be readily done by pressing down upon the button 21, against the spring action of the tongue 7, until the lug or bar 20 is forced out of the locking groove 8, which will then permit the spring tongue to lift the movable jaw 15, with its rubber or

other facing 17, into the position shown in Fig. 2, when the stocking or other fabric can be readily removed.

I have shown a modification of my invention in Fig. 7, which is a duplex garment holder formed of two of my individual garment holders connected together by resilient means, such as a spring 25, so that one of the garment holders can be secured to a corset or other support, and the other garment holder can be secured to a stocking.

I have shown another modification of my invention in Fig. 8, which is also a duplex garment holder formed of two of my individual garment holders secured together in any suitable manner, such as by the rivet 26.

Having thus described this invention in connection with illustrative embodiments thereof, to the details of which I do not desire to be limited, what is claimed as new and what is desired to secure by Letters Patent is set forth in the appended claims.

What I claim is:—

1. A garment holder comprising a fixed jaw faced with resilient material, a jaw faced with resilient material, and movable to successively parallel positions toward and away from the fixed jaw means to yieldingly press the movable jaw towards the fixed jaw, and means to lock the movable jaw in its operative position to clamp an interposed fabric.
2. A garment holder formed of two substantially rigid members arranged parallel to each other, and one of them forming a fixed jaw, a jaw mounted between the parallel substantially rigid members, and movable to successively parallel positions toward and away from the fixed jaw and means to yieldingly press the movable jaw against the fixed jaw to clamp a fabric.
3. A garment holder formed of two substantially rigid members arranged parallel to each other, and one of them forming a fixed jaw, a jaw mounted between the parallel substantially rigid members, and movable to successively parallel positions toward and away from the fixed jaw and means to yieldingly press the movable jaw against the fixed jaw, and means to lock the movable jaw in its operative position to clamp a fabric.
4. A garment holder formed from sheet metal bent back on itself to form two substantially parallel rigid members, one of which is the fixed jaw of the garment holder, a movable jaw, a spring tongue stamped from one of the rigid members and connected to the movable jaw.
5. A garment holder formed from sheet metal bent back on itself to form two substantially parallel rigid members, one of which is the fixed jaw of the garment holder, a movable jaw, a spring tongue stamped from one of the rigid members and con-

nected to the movable jaw, and cooperating locking members carried by the spring tongue and one of the rigid members to lock the movable jaw in its operative position.

6. A garment holder formed from sheet metal bent back on itself to form two substantially parallel rigid members, one of which is the fixed jaw of the garment holder, a movable jaw, a spring tongue stamped from one of the rigid members and connected to the movable jaw, one of the rigid members being provided with a groove and the spring tongue having a lug or bar to lock the tongue with its movable jaw in operative clamping position.

7. A sheet metal blank from which a garment holder is adapted to be formed, comprising a rectangular piece of metal one end of which is provided with one or more ears adapted to be bent over to hold a yielding facing, the other end of the blank having two slots to form a tongue, and cooperating locking surfaces on the tongue and the end of the blank from which the tongue is formed.

8. A duplex garment holder comprising two separate garment holders each having a fixed jaw faced with resilient material, a jaw faced with resilient material, and movable to successively parallel positions toward and away from the fixed jaw, means to yieldingly press the movable jaw towards the fixed jaw to clamp an interposed fabric, means to lock the movable jaw in operative position, and means to connect the respective garment holders together.

9. A duplex garment holder comprising two separate garment holders each having a fixed jaw faced with resilient material, a jaw faced with resilient material, and movable to successively parallel positions toward and away from the fixed jaw, means to yieldingly press the movable jaw towards the fixed jaw to clamp an interposed fabric, means to lock the movable jaw in operative position, and resilient means to connect the respective garment holders together.

10. In a garment supporter the combination of substantially flat fixed and movable jaws, resilient means for moving the movable jaw to successively parallel positions toward and away from the fixed jaw, and means for locking the movable jaw in clamping position.

11. A garment supporter comprising two fixed members connected at one end to form a substantially U-shaped structure, a movable jaw mounted between said fixed members, a spring tongue for supporting the movable jaw, and for moving it to and from gripping position when an endwise force is exerted on the tongue, and means for locking the spring tongue in clamping position.

12. In a garment supporter, the combination of fixed and movable jaws, a spring tongue connected to the movable jaw, means for exerting an endwise force on the spring tongue whereby it is caused to bend or flatten for moving the movable jaw to and from clamping position, and means for locking the movable jaw in clamping position.

13. A garment supporter comprising two fixed members connected at one end to form a substantially U-shaped structure, a spring tongue, one end of which is attached to one of said fixed members and the other end of which is slidably engaged with the same fixed member, a movable clamping jaw attached to the spring tongue intermediate

its ends, and means for locking the spring tongue for holding the movable jaw in clamping position.

14. In a garment supporter, the combination of two fixed members, a spring tongue stamped from one of said fixed members, and having one end slidably engaged therewith, a movable clamping jaw supported by the spring tongue intermediate its ends, and means for locking the slideable end of the spring tongue to said fixed member for holding the clamping jaw in fixed position.

In testimony whereof, I have signed my name to this specification.

ABRAHAM PFLANTZER.
